MODEL RACING CAR

Robert John Herd, Milton Malsor, England, assignor to March Engineering Limited, Bicester, Oxfordshire, England

Filed July 30, 1970, Ser. No. 24,222

Claims priority, application Great Britain Jan. 30, 1970

Term of patent 7 years

Int. Cl. D21—01

U.S. Cl. D34—15

FIG. 1 is a top plan view of a model racing car showing my new design;

FIG. 2 is a front elevational view thereof;

FIG. 3 is a right side elevational view of FIG. 1, the left side being a mirror image thereof; and

FIG. 4 is a rear elevational view thereof.

I claim:

The ornamental design for a model racing car, as shown and described.
